William Faison,
By his Attorney,
Stephen Utick

United States Patent Office.

WILLIAM FARSON, OF PHILADELPHIA, PENNSYLVANIA.

Letters Patent No. 98,942, dated January 18, 1870.

IMPROVED EXTENSION-TABLE.

The Schedule referred to in these Letters Patent and making part of the same.

I, WILLIAM FARSON, of the city of Philadelphia, and State of Pennsylvania, have invented a new and useful Improvement in Connecting the Leaves of Extension-Tables, of which the following is a specification.

The nature of my invention consists in the connection of the auxiliary leaves of the table, by means of slotted metallic plates and headed pins, the plates being fastened in one edge of the leaves, and the pins in the other edge. The slots in the plate have an enlargement at one end, through which the heads of the respective pins pass, until they come inside of the plates as the leaves are successively brought together. The leaves are then pushed forward, until their ends come into line with the ends of the tops of the tables, as hereinafter described.

To enable others skilled in the art to which my improvement appertains, to make and use my invention, I will now give a detailed description thereof.

In the accompanying drawings, which make a part of this specification—

Figure 1 is a plan view of the top of the table, with the leaves in connection, one of the leaves being in position to be connected.

Figure 2 is an edge view of the auxiliary leaf B.

Figures 3 and 4 are a face and edge view of one of the plates C, full size.

Figure 5 is a perspective view of one of the screws D, full size.

Like letters in all the figures indicate the same parts.

A, A' represent the tops of the end tables, between which any number of auxiliary leaves, B, B', are connected.

In one edge of the leaves B, B', there are plates C, which are sunk flush with the same, and confined in place by means of screws a, as seen in fig. 2.

In the connecting edge of the top A there are screws D, D', which have heads, b, that are slipped through the slots c, at the enlargement c', when the leaf B is in the position represented by dotted lines. Then the leaf is pushed forward until it comes into the position represented by full lines, the shoulder d of the heads b bearing against the inside face of the plates, the di-

ameter of the stem of the screws being a trifle less than the width of the slot c, so as not to prevent the easy movement of the leaf.

There is a recess, e, back of the plates C, for the passage of the head of the screws, as seen in figs. 1 and 2. The next leaf is then brought into the position represented by full lines, and connected in like manner.

If it is the last leaf to be connected, as represented in the drawings, the top A' is pushed into the position represented by dotted lines, and then the leaf is pushed forward, in range with the continued dotted end line, and the rest of combined table-top; and thus the leaves and tops are held firmly together.

One of the screws, D, is shown in detail in fig. 5.

If desired, plain pins, having heads b, may take the place of the screws D.

I arrange the plates C and screws D in such a manner that there may be no obstruction in bringing the tops A and A' together, for connection in the usual way, when the auxiliary leaves B, B', are not used. I first connect the plates and screws with the connecting edges of the tops A and A', so that when the ends of the top are in line, the heads b of the screws may slip through the enlargement c' of the slots c of the plates, and then arrange the plates and screws with the auxiliary leaves, to correspond with this arrangement, the pins and plates being all on a line with each other.

What I claim as new, and desire to secure by Letters Patent, is—

The plates C, and pins or screws D, in combination with the edges of the tops A and A', and the auxiliary leaves B, B', whereby the leaves are held in place, substantially in the manner hereinbefore described.

In testimony that the above is my invention, I have hereunto set my hand, and affixed my seal, this 24th day of December, 1869.

WILLIAM FARSON. [L. s.]
